UNITED STATES PATENT OFFICE.

LOUIS K. SCOTFORD, OF CHICAGO, ILLINOIS.

VULCANIZING-PRESS.

SPECIFICATION forming part of Letters Patent No. 623,838, dated April 25, 1899.

Application filed February 10, 1898. Serial No. 669,755. (No model.)

To all whom it may concern:

Be it known that I, LOUIS K. SCOTFORD, of Chicago, in the county of Cook and State of Illinois, have invented certain new and useful 5 Improvements in Vulcanizing-Presses; and I do hereby declare that the following is a full, clear, and exact description thereof, reference being had to the accompanying drawings, and to the letters of reference marked thereon, 10 which form a part of this specification.

This invention relates to an improved apparatus for use in vulcanized articles of rubber—such, for instance, as rubber type-sheets used in hand-stamps.

15 The invention relates more particularly to an apparatus of that class in which the article to be vulcanized is subjected to direct pressure of opposing surfaces and at the same time subjected to the action of heat communicated thereto from said opposing surfaces, said apparatus being in this respect like that shown in my prior patent, No. 407,255, granted July 16, 1889.

25 The invention consists in the matters hereinafter set forth, and more particularly pointed out in the appended claims.

In the drawings, Figure 1 is a front elevation of an apparatus constructed in accordance with my invention. Fig. 2 is a side elevation thereof. Fig. 3 is a vertical section taken on line 3 3 of Fig. 1. Fig. 4 is a detailed section taken on line 4 4 of Fig. 2. Fig. 5 is a detail section taken on line 5 5 of Fig. 2.

As shown in said drawings, A designates 35 the lower part or platen of the press, which is supported upon legs or standards B, and C designates the upper part or follower thereof. Said platen consists of a hollow casting, which is herein shown as of rectangular shape, as 40 seen in plan view, at the upper part thereof. Said hollow platen is provided in its lower part with a cylindric cup-shaped water-receptacle A', forming a steam-generator, and is closed at its upper part by a flat horizontal wall A², which constitutes the supporting-surface of the platen, between which and the follower the rubber is compressed. Said platen is provided at its opposite sides, in the upper part thereof, with upwardly-extending side 45 pieces or flanges A³ A³, which form the sides of a chamber C', in which the follower C is located and of which the supporting-surface

of the platen forms the bottom or floor. Said chamber is closed at its upper end by means of a plate or wall A⁴, which is secured in place 55 by means of tap-bolts a a, passing through the margins thereof and into the upper edges of the side walls A³. The rear wall of said chamber is formed by a depending flange A⁵, secured upon or formed integral with the rear end of the plate A⁴, and said rear wall rests when said plate is in place between the side walls A³. The said chamber C' is without any front wall and is provided at its front 60 part with an opening A⁷, through which the matrix and the rubber to be vulcanized may be inserted into and removed from said chamber. Said upper wall A⁴ is provided centrally with a hub A⁶, through which passes a screw-shaft C², which bears at its inner end upon 65 the top of the follower C and is provided with a hand-wheel C³. Said plate or wall A⁴ is provided in the corners thereof with set-screws a' a', which are adapted to be screwed down upon the follower C to hold the latter in contact with the rubber to be vulcanized independently of the central shaft C², by which latter said follower is raised and lowered. 70

The follower C is preferably made to fit closely within the air-chamber C' and is sustained in a position parallel with the supporting-surface A² of the hollow platen by the shaft C². In order to afford the necessary stiffness or rigidity to the said follower to prevent it from bending under the strain coming 80 thereon when the form is clamped between the platen and follower, the latter is provided with a centrally-arranged hub or boss C⁴, which extends above the plate forming the follower, preferably convex in form, and with the top 85 of which the screw-threaded shaft C² is engaged. Any other construction in the follower to give stiffness thereto may be used, however, as found most convenient or desirable. The upper wall A⁴ of the hot-air chamber C' 90 is bulged outwardly to form in its inner surface a concave recess adapted to receive the portion C⁴ of the follower when the latter is moved away from the platen A. Such construction of the wall A⁴ also serves to provide 95 greater strength and rigidity in the same to resist the upward thrust of the shaft C² when the follower C is screwed down upon the platen A. 100

The platen A is provided exteriorly above the water-receptacle with an offset portion or recess a^2 , within which the upper ends of the standards or legs B rest and by which the 5 said platen is supported. That part of the hollow platen between the water-receptacle A' and the upper supporting wall or surface A^2 thereof constitutes a steam-chamber, into which the steam passes from the water-re- 10 ceptacle.

a^3 designates a water-feed pipe which opens into the interior of the platen above the water-receptacle, and a^4 a water-pipe by which the water in the receptacle may be maintained to 15 a predetermined height.

a^5 designates a pressure-gage connected with the hollow platen by a pipe a^6 , and a^7 a safety-valve connected with the interior of the platen. The pressure-gage affords a con- 20 venient means for determining the pressure of the steam, and thereby regulating the temperature of the pressing-surfaces.

The water-receptacle A' may be heated in any preferred manner. As herein shown, a 25 gas-burner D is located upon a supporting-plate E beneath said receptacle, said burner being supplied with fuel through the medium of a pipe D'. As a means for preventing the flame of the burner from being deflected by 30 drafts of air and also to retain the heat under the water-receptacle a jacket or shield E' of sheet metal is placed around the burner, said shield extending upwardly to within a short distance of said water-receptacle at the line 35 of its greatest diameter. As a preferred construction the side walls of said jacket E' are connected with the supporting-plate E, and said jacket and plate are held in position by means of bolts b, which are tapped through 40 the legs or standards B and upon the inner ends of which said plate and jacket are sustained. Said standards will desirably be provided with marginal longitudinally-extending 45 flanges b', which form guides to engage the adjacent corners of the jacket and by which said jacket is held from lateral movement. Said jacket is provided in one of its outer walls with a port or opening E², through 50 which the flame is visible from the outside thereof, and is provided in the horizontal part E with air-inlet openings e e, through which air enters to reach the burner D.

Steam will be generated in the hollow platen A to a predetermined pressure, when it will 55 escape through the safety-valve a^7 , by means of which the pressure of the steam within said platen and the temperature of the pressing-surfaces can be controlled. The movable follower C is not directly connected with the 60 steam-chamber of the hollow platen, as in the construction of my said prior patent; but said movable follower or upper pressing-plate is heated by heat transmitted from the steam within the hollow platen, through the sup- 65 porting or pressing surface A^2 of the hollow platen, to the air within the chamber C' and also to some extent through the side walls of

the chamber and the mold between the platen and follower when said mold is clamped between the same.

I have found by experiment that the pressing-surfaces of the follower and platen made as described may be maintained at a practically equal temperature and that the results obtained are substantially as good as in the 75 construction wherein the movable follower is made hollow and is connected with the hollow platen in which the steam is generated by connecting-pipes, as in the construction of my said prior patent.

In the use of the apparatus described for making a rubber printing-sheet a mold or matrix having the reverse of the types or printing characters desired is placed upon the platen with the sheet of rubber, prepared in 80 readiness for the application of heating-pressure, in contact with the same. The follower is then brought against the rubber to force the same into contact with all the parts of the matrix. After the follower has been 85 forced against the rubber by the use of the hand-wheel C³ the set-screws a' of the upper wall A^4 of the chamber C' are then forced down against the follower by the use of a suitable tool, so that said follower is held rigidly 90 in place while the process of vulcanizing is taking place without reliance upon the shaft C² for giving pressure, said shaft being used mainly for the purpose of lifting and lowering the follower. The set-screws may also be 95 used for the purpose of forcing down the follower with greater pressure than can be exerted by the use of the hand-wheel alone. In order to prevent the central screw-shaft from interfering with the action of the set- 100 screws a' when said screws are moved downwardly against the follower, said follower has a freedom of vertical movement to a limited extent with relation to the upper wall A^4 of the air-chamber C'. Such freedom of move- 105 ment may be provided either between the shaft and said upper wall or between the shaft and the follower. The latter arrangement is herein shown and is made as follows: The shaft is provided at its inner end with 110 an outwardly-extending flange c, which fits within a socket on said follower, herein shown as consisting of a detachable aper- 115 tured block c', secured to the follower by bolts in the manner shown. Said block is pro- 120 vided with a radially inwardly extending flange c², which overlaps the flange c of the shaft and prevents the same from becoming detached therefrom. The depth of the socket inside the flange c² is greater than the width 125 of the flange c, so that in the upward move- 130 ment of the shaft the flange c will engage the flange c² and in the downward movement thereof it will engage the upper surface of the follower, thereby affording lost motion 135 between the shaft and follower sufficient to permit the set-screws to advance the follower to a necessary extent after it has been carried against the work by the screw-shaft.

As a further improvement in apparatus of the class described the hot-air chamber C' is provided with a removable or sliding drawer which receives the matrix and which is inserted into and removed from the chamber through the opening A⁷ at the front wall thereof. Said drawer consists of a flat plate G, which when in place rests upon the supporting-surface A² of the hollow platen and is of such size as to entirely cover the same. To the forward end of said plate is attached an upwardly-extending plate or flange G', which is of such size as to overlap the margins of and entirely cover the opening A⁷ of the chamber C' and which forms when in place the front wall of the said chamber. The plate or flange G' is provided with a handle G² by which the drawer may be manipulated.

As a convenient construction the apparatus will be provided with a shelf or ledge A⁸, which forms an extension of the supporting-surface A² of the hollow platen at the front part thereof and which is adapted to receive the drawer when it is withdrawn from the hot-air chamber C'. As a further improvement and in order to prevent the drawer from being accidentally moved off the shelf when withdrawn from the chamber C' said drawer is provided on its opposite side thereof with depending guide-lugs g g, which engage the opposite margins of the shelf to prevent lateral movement of the drawer upon said shelf. Said shelf is also provided in its outer end with stop-pins g' g', which limit the outward movement of the drawer thereon.

The matrix employed for giving shape to the articles of rubber, such as rubber type-sheets, are made of a compound containing plaster and other ingredients and which requires heating or baking to harden the same preparatory to the application of the rubber sheets thereto, the means provided in my said prior construction for so hardening or baking the matrix consisting of a hot-air chamber or oven provided especially for that purpose and located above the movable follower, so that it was necessary to remove said matrix after being dried or hardened in said air-chamber and place the same between the platen and the follower after the rubber sheet had been applied thereto. In the present construction the matrix will be heated to harden the same by placing it within the hot-air chamber C' beneath the follower when the same is lifted to give room for the matrix. In practice the matrix will first be placed on the bottom plate of the drawer and the latter then thrust into the hot-air chamber and allowed to there remain until properly dried or hardened. The drawer will then be pulled out and the rubber sheet applied to the matrix. The drawer will then again be thrust in and the follower forced down upon the rubber sheet and matrix to press or squeeze the same together. The parts will be allowed to remain in this condition until the rubber has been

acted upon by the heat long enough to produce proper vulcanization thereof. The operation of drying the matrix and vulcanizing is thereby much simplified.

The main feature of my invention is comprised in the construction in which the movable follower and supporting-surface of the hollow platen are contained within a chamber which forms an inclosure adjacent to the heated surface of said hollow platen to receive heat from the heating medium thereof, but which itself is not provided with heating means. This engagement simplifies the construction of the apparatus by obviating the necessity of providing connections through which a heating medium, such as steam, may be transmitted to the follower which connections are required to be made flexible to permit movement of said follower and which are expensive to construct and require constant attention to prevent escape of the heating medium therefrom.

Another important feature of my invention which arises from the fact that the heating medium is not introduced directly to the follower or the chamber containing the same is that the chamber which is used to aid in the application of heat to the rubber sheet while pressure is being applied thereto in the process of vulcanizing may be used for drying the matrix. The construction by which this result is obtained is not only much simpler than the prior constructions and cheaper to manufacture, but also greatly simplifies the operation of drying the matrices and afterward applying thereto the rubber sheets to be vulcanized. Moreover, such construction enables the apparatus to be made of more compact form and to occupy less space in a factory than the prior constructions, containing in one machine the drying and heating devices.

A further practical advantage gained by the use of the construction described is that the follower is contained entirely within the hot-air chamber, the upper wall of said chamber serving as a yoke with which the screw-threaded shaft of the follower is engaged. Such construction affords great compactness, while the apparatus occupies a minimum of space and is at the same time more economical to manufacture.

For the general purpose of my invention the water-receptacle need not be located as herein illustrated, but steam may be supplied to the hollow platen from any suitable source or means of steam-supply. Moreover, it is obvious that the hollow platen may be placed above the hot-air chamber and the arrangement of the parts reversed, so that the follower will move upwardly against the platen. The arrangement herein illustrated, however, is a desirable one in point of simplicity and convenience, and is therefore made the subject of specific claims herein.

I claim as my invention—

1. An apparatus for the purpose set forth, comprising a hollow stationary platen pro-

vided with a water-receptacle in connection with the interior thereof and forming a steam-generator, a movable follower, and a chamber inclosing the follower.

- 5 2. The combination with a platen, a follower movable toward and from the platen, a chamber containing the follower, a screw-threaded shaft engaging the wall of said chamber and acting upon said follower, a plurality of set-screws having screw-threaded engagement with the said wall of the chamber and acting upon said follower, said parts being constructed to afford lost motion between said follower and the wall of the chamber.
- 15 3. The combination with a platen, a follower movable toward and from the platen, a plate supported above said follower and a screw-threaded shaft engaging said plate and acting upon the follower, of a plurality of bolts having screw-threaded engagement with the plate and acting upon said follower, said shaft being connected with the follower by means affording lost motion between the same.
4. The combination with a platen having a horizontal supporting-surface, a follower, top and side walls forming a chamber which surrounds the follower and is provided with an opening in one of its side walls, a drawer adapted to be inserted into said chamber
- 25 through said opening, and a shelf having its upper surface in the same plane with the supporting-surface of the platen and adapted to
- 20
- 25
- 30

receive said drawer when the latter is withdrawn from the chamber.

5. The combination with a platen having a horizontal supporting-surface, a follower, top and side walls forming a chamber which 35 encloses the follower and which is provided with an opening in one of its side walls, a drawer adapted to be inserted into said chamber through said opening, and a shelf having its upper surface in the same plane with the supporting-surface of the platen, and adapted to receive said drawer when the latter is withdrawn from the chamber, said drawer being 40 45 provided with guide-lugs which engage guide-surfaces on the shelf.

6. An apparatus for the purpose set forth comprising a hollow stationary platen, a chamber located above said platen, the bottom floor 50 of which is formed by the upper wall of the platen, a follower in said chamber movable toward and from said platen and a sliding drawer in said chamber, the outer part of which forms one of the walls of the chamber. 55

In testimony that I claim the foregoing as my invention I affix my signature, in presence of two witnesses, this 8th day of February, A. D. 1898.

LOUIS K. SCOTFORD.
